UNITED STATES PATENT OFFICE.

LANSING ONDERDONK AND AUGUST J. WOHLPART, OF NEW YORK, N. Y., ASSIGNEES
TO UNION SPECIAL MACHINE COMPANY, OF CHICAGO, ILLINOIS, A CORPORATION
OF ILLINOIS.

FEEDING MECHANISM FOR CUP-FEED MACHINES.

Application filed December 14, 1921. Serial No. 522,359.

To all whom it may concern:

Be it known that we, LANSING ONDERDONK and AUGUST J. WOHLPART, citizens of the United States, both residing at New York, 5 in the county of New York, State of New York, have invented certain new and useful Improvements in Feeding Mechanisms for Cup-Feeed Machines, of which the following is a description, reference being had 10 to the accompanying drawing and to the figures of reference marked thereon.

The invention relates to new and useful improvements in cup feed machines, and more particularly to the feeding mechanism 15 thereof.

An object of the invention is to provide a feeding mechanism for operating intermittently the inner and outer feed cups, which includes devices whereby the feed 20 stroke imparted to the feed cups may be independently adjusted so that, either the inner or outer feed cup may be caused to feed a little faster than the other, if desired.

A further object of the invention is to 25 provide a feeding mechanism for the feed cups wherein the feed strokes of the cups may not only be independently adjusted but wherein the feed strokes may be simultaneously adjusted.

These and other objects will in part be 30 obvious and will in part be hereinafter more fully disclosed.

In the drawings, which show by way of 35 illustration one embodiment of the invention:—

Figure 1 is a side view of a machine embodying the improvements, a portion of the belt wheel being broken away to show the parts in rear thereof;

Fig. 2 is a plan view of the machine;

Fig. 3 is a horizontal sectional view midway through the machine with certain parts broken away and certain parts omitted so as to show clearly the train of devices for 45 actuating the inner feed cup;

Fig. 4 is an enlarged side view of the lower portion of the machine with parts broken away to show more clearly the feeding mechanism.

The invention is directed broadly to a machine of the cup feed type, that is, a machine having feed wheels rotated about vertical axes for supporting and feeding ma-

terial to a horizontally arranged needle. Cooperating with the needle is means for forming an overedge stitch. The inner feed cup is operated by a train of devices which includes an intermittently operated clutch for turning the feed wheel step by step. This train of devices includes means whereby the extent of movement imparted to the inner feed cup or wheel may be varied. The outer cup or wheel is also operated intermittently by a train of devices which includes means whereby the length of the feed stroke of said outer feed cup or wheel may be varied. These trains of devices for operating the inner and outer feed wheels include also a common connection with the driving shaft, and the parts making up this common connection with the driving shaft preferably include means whereby the stroke of both the inner and outer feed wheels may be simultaneously varied.

Referring more in detail to the drawings, 75 the invention is shown as applied to a cup feed machine of the type disclosed in Patent No. 1,246,302, granted to J. R. Moffatt, November 13, 1917. Said machine includes a casing 1, in which is mounted a main shaft 80 2. Also mounted to reciprocate in the casing is a needle bearing carrying a needle 3. Cooperating with the needle 3 is a looper 4, which looper is so mounted and actuated as to form overseaming stitches. The material 85 is held in a vertical position and directed to the needle, which reciprocates in a horizontal line, by feed cups or wheels 5 and 6.

The feed cup 5 is carried by a shaft 7, which is mounted in suitable bearings carried by a casing 8 attached to the main casing of the machine. Adjacent the lower end of the shaft 7 there is a clutch disk 9. Associated with the clutch disk 9 is an actuating clutch plate 10 which carries a hub 95 11. Clutch dogs 12, 12 are provided with grooves adapted to engage the flange of the clutch disk 9, and these clutch dogs rest against shoulders formed on the hub 11. Associated with the clutch dogs are springs 100 13. This intermittently operating clutch is of the usual construction, and further description thereof is not thought necessary.

There is also a clutch dog 14 which prevents the feed cup from being turned in the wrong direction. The actuating plate 10 is

oscillated, and as said plate is oscillated it will intermittently turn the shaft 7 in a clockwise direction, as viewed in Fig. 3. Said clutch actuating plate 10 is vibrated by 5 means of a link 15 which is connected to a ball stud 16 carried by the clutch plate, and to a ball stud 17 adjustably mounted in a slot 18 formed in an arm 19. The arm 19 is fixed to the lower end of a shaft 20. This shaft 10 20 is mounted in bearings 21 and 22 carried by the casing 1. The shaft 20 is adapted to be oscillated, and as said shaft oscillates it will impart vibrations to the clutch plate 10, and this in turn will rotate the shaft 7 15 intermittently or step by step.

The feed wheel 6 is mounted to rotate in a bracket 23 which is pivotally mounted at 24 so that said feed wheel may be bodily swung away from the inner feed wheel 5 to permit 20 the insertion of the material. Said bracket 23 is normally swung so as to hold the feed wheels yieldingly in contact with each other by means of a spring 25, and said bracket 25 may be swung in the opposite direction by means of a lever 28 which is connected to a knee shift or treadle.

The feed wheel 6 is connected by a suitable series of gears to a gear wheel 29, shown in dotted lines in Fig. 1, and this gear wheel 30 29 is carried by a vertical shaft 30, also shown in dotted lines in said figure. On the upper end of the shaft 30 there is a clutch mechanism similar to that shown more in detail in Fig. 3. Said clutch mechanism includes a clutch actuating plate 31, clutch dogs 32, shown in dotted lines in Fig. 2, and a clutch disk connected to the shaft 30 upon which said dogs are adapted to grip for intermittently turning the shaft 30. Clutch 35 actuating plate 31 carries a ball stud 33, to which one end of a link 34 is connected. The other end of this link 34 is connected to a ball stud 35 which is adjustably mounted in a slot 36 formed in an arm 37 which is connected to the upper end of the shaft 20. As 40 the shaft 20 oscillates, it will move the link 34 back and forth and impart intermittent or 45 step by step movement to the outer feed wheel 6.

By adjusting the position of the ball stud 35 in the slot 36, the length of the feed movement imparted to the outer feed wheel may be varied. Likewise by adjusting the stud 50 17 in the slot 18 in the arm 19, the feed 55 stroke of the inner feed wheel may be varied, and while both these feed wheels are intermittently operated from the same shaft 20, these devices afford means whereby the feed stroke of either feed wheel may be varied 60 relative to the other so that said feed wheels may be caused to move to feed the material in unison or one feed wheel feed or crowd the material a little faster than the other to suit whatever class of work is being done.

The shaft 20 is provided with an arm 37.

This arm 37 carries a ball stud 38 with which a link 39 is connected. The stud 38 is mounted for adjustment in a slot 40 formed in said arm 37, and indicated in dotted lines in Fig. 3. The link 39 at its other end 70 is connected to a ball stud 41 carried by a lever 42 which is pivoted to swing about a fulcrum center 43. The inner end of the lever 42 carries a ball stud 44, to which an eccentric strap 45, cooperating with an eccentric 75 46 on the main shaft 2, is connected.

It will readily be seen that by adjusting the ball stud 38 the extent of oscillation imparted to the shaft 20 may be varied, and this will simultaneously vary the feed strokes 80 of both the inner and outer feed wheels. It will be apparent, therefore, that we have provided a feeding mechanism for a cup feed machine wherein the feed stroke of the inner and outer feed wheels may be independently 85 adjusted and wherein the feed stroke of the inner and outer feed wheels may likewise be simultaneously adjusted.

It is obvious that minor changes in the details of construction and the arrangement 90 of the parts may be made without departing from the spirit of the invention as set forth in the appended claims.

Having thus described the invention, what we claim as new is:—

1. A sewing machine including in combination, feed wheels between which a fabric is clamped and fed to a stitching mechanism, means for independently rotating said feed wheels including devices whereby the feed strokes of said feed wheels may be independently varied.

2. A sewing machine including in combination, feed wheels between which a fabric is clamped and fed to a stitching mechanism, means for independently rotating said feed wheels including devices whereby the feed strokes of said feed wheels may be independently varied, said devices also including means whereby the feed strokes of said feed wheels may be simultaneously varied and to the same extent.

3. A sewing machine including in combination, feed wheels between which a fabric is fed to stitching mechanism, an intermittently actuating clutch for rotating one of said feed wheels, and a separate intermittently actuating clutch for rotating the other feed wheels, and devices for actuating said clutches including means whereby the feeding strokes imparted by said clutches may be independently varied.

4. A sewing machine including in combination, feed wheels between which a fabric is fed to stitching mechanism, an intermittently actuating clutch for rotating one of said feed wheels and a separate intermittently actuating clutch for rotating the other feed wheel, and devices for actuating said clutches including means whereby the feed-

ing strokes imparted by said clutches may be independently varied, said devices also including means whereby the feeding strokes imparted to said clutches may be simultaneously varied to the same extent.

5. A sewing machine including in combination, feed wheels between which a fabric is fed to stitching mechanism, an intermittently actuating clutch for operating one of 10 said feed wheels, an intermittently actuating clutch for operating the other feed wheel, a shaft, means for oscillating said shaft, devices connecting said shaft to one of said clutches, and devices connecting said 15 shaft to the other clutch, said devices connecting the clutches to the shaft including means whereby the feed strokes of the clutches may be independently varied.

6. A sewing machine including in combination, feed wheels between which a fabric is fed to stitching mechanism, an intermittently actuating clutch for operating one of said feed wheels, an intermittently actuating clutch for operating the other feed 20 wheel, a shaft, means for oscillating said shaft, devices connecting said shaft to one of said clutches, and devices connecting said shaft to the other clutch, said devices connecting the clutches to the shaft including means 25 whereby the feed strokes of the clutches may be independently varied, said means for oscillating the shaft including devices whereby the oscillating movement imparted 30 to the shaft may be varied.

35 7. A sewing machine including in combination, a horizontal reciprocating needle, an inner feed wheel, means for actuating the same, an outer feed wheel, a bracket pivoted above said needle and supporting 40 said outer feed wheel, a shaft connected to the outer feed wheel, an intermittent clutch connected to the upper end of said shaft, a link having a ball stud connection with said clutch for operating the same, a vertical shaft having an arm carrying a ball stud to 45 which said link is connected, and means for swinging the bracket to separate said feed wheels.

50 8. A sewing machine including in combination, a horizontal reciprocating needle, an inner feed wheel, means for actuating the same, an outer feed wheel, a bracket pivoted above said needle and supporting said outer feed wheel, a shaft connected to the outer 55 feed wheel, an intermittent clutch connected to the upper end of said shaft, a link having a ball stud connection with said clutch for operating the same, a vertical shaft having an arm carrying a ball stud to which 60 said link is connected, and means for swinging the bracket to separate said feed wheels, said ball stud carried by the arm of the vertical shaft being adjustably attached thereto whereby the feed stroke of the outer feed 65 wheel may be varied.

9. A sewing machine including in combination, a horizontal reciprocating needle, an inner feed wheel, means for actuating the same, an outer feed wheel, a bracket pivoted above said needle and supporting said outer 70 feed wheel, a shaft connected to the outer feed wheel, an intermittent clutch connected to the upper end of said shaft, a link having a ball stud connection with said clutch for operating the same, a vertical shaft having 75 an arm carrying a ball stud to which said link is connected, and means for swinging the bracket to separate said feed wheels, said ball stud carried by the arm of the vertical shaft being adjustably attached thereto whereby the feed stroke of the outer feed wheel may be varied, said means for operating the inner feed wheel including a link, an arm carried by the vertical shaft and having adjustable connections with said link whereby the stroke of the inner feed 80 wheel may be varied.

10. A sewing machine including in combination, a horizontal reciprocating needle, an inner feed wheel, means for actuating the same, an outer feed wheel, a bracket pivoted above said needle and supporting said outer feed wheel, a shaft connected to the outer feed wheel, an intermittent clutch connected to the upper end of said shaft, a link having a ball stud connection with said clutch for operating the same, a vertical shaft having an arm carrying a ball stud to which said link is connected, and means for swinging the bracket to separate said feed wheels, said ball stud carried by the arm of the vertical shaft being adjustably attached thereto whereby the feed stroke of the outer feed wheel may be varied, said vertical shaft having an intermediate arm, a link adjustably connected thereto, a lever to which said link is connected, a main shaft, an eccentric on said main shaft, and an eccentric strap operated by said eccentric and connected to said lever.

11. In a sewing machine of the class described, a pair of adjacently placed feed cups, devices for imparting an intermittent revoluble movement positively to both feed cups, means for operating the said means, and devices for separately adjusting the extent of the movement of each feed cup.

12. In a sewing machine of the class described, adjacently placed feed cups, devices for imparting an intermittent revoluble movement positively to both feed cups, means for operating the aforesaid means, devices for separately adjusting the extent of movement of each feed cup, and devices for simultaneously adjusting the extent of the movement of both feed cups.

13. In a sewing machine of the class described, a frame, an inner feed cup mounted in the frame, an overhanging rocker arm pivotally mounted in the frame, an outer 130

feed cup mounted in the said rocker arm, means for imparting an intermittent revoluble movement to the said inner feed cup, means for imparting an intermittent revoluble movement to the outer feed cup, and adjustable means for separately regulating the extent of movement of each feed cup.

14. In a sewing machine of the class described, a frame, an inner feed cup mounted in the frame, an overhanging rocker arm pivotally mounted in the frame, an outer feed cup mounted in the said rocker arm, means for imparting an intermittent revoluble movement to the said inner feed cup, means for imparting an intermittent revoluble movement to the outer feed cup, adjustable means for separately regulating the extent of movement of each feed cup, and

means for simultaneously adjusting the extent of the movement of both feed cups. 20

15. In a sewing machine of the class described, a frame, a drive shaft mounted therein, a rocker arm mounted in the frame, a feed cup carried by the rocker arm, a feed cup mounted in the frame, devices for imparting intermittent partial revoluble movements to the said feed cups, a rocker shaft journaled in the said frame, means for operating the rocker shaft from the said drive shaft, and means for separately actuating the said devices for moving the said feed cups from the said rocker shaft. 25

In testimony whereof, we affix our signatures.

LANSING ONDERDONK.
AUGUST J. WOHLPART.
